C. F. Taylor,

Truss.

No 26,628.

Patented Dec. 27, 1859.

UNITED STATES PATENT OFFICE.

CHARLES F. TAYLOR, OF NEW YORK, N. Y.

APPARATUS FOR RELIEVING SPINAL CURVATURE.

Specification of Letters Patent No. 26,628, dated December 27, 1859.

To all whom it may concern:

Be it known that I, CHARLES F. TAYLOR, of New York, in the county of New York, and State of New York, have invented a 5 Spinal Assistant Designed to Aid in the Treatment of Angular Curvature of the Spine, the construction and operation of which I have described in the following specification and illustrated in its accompanying drawings with sufficient clearness 10 to enable competent and skilful workmen in the arts to which it pertains or is most nearly allied to make and use my invention.

The upright columns that assist the spine 15 are, in my instrument, provided with one or more stop hinges so arranged that while forward flection of the trunk is prevented, there is no hindrance to its backward flection, the object being to enable the spinal 20 muscles to act and thus become developed, so that said spinal muscles may assist in the reduction of the curvature and aid in arresting the diseased process by relieving the anterior plates of the vertebrae from pressure 25 at the point of disease, and by this encouragement of the action of the posterior muscles of the trunk causing healthy tissue to exist in the vicinity of the disease, at the same time allowing all motions of the body 30 except those which it is necessary to prevent, namely: Forward and lateral flection through the diseased point, thereby exerting a wholesome influence upon the general health of the patient. My instrument is still 35 further so constructed that pressure is made at the anatomical points known as the angles of the ribs, for the following reasons, namely: Pressure at the angles of the ribs secures a more solid rest for the instrument 40 to act against; by partially embracing the spine prevents lateral flection through the diseased point; has a tendency to elevate the anterior extremities of the ribs and thus throw back the upper portion of the spine; 45 avoids the injurious effects of pressure on the spinal muscles; and especially avoids the injury, resulting from pressure on the wedge shaped, diseased vertebrae at the angular projection of the spine; secures great 50 steadiness of the trunk with slight force of contact of the instrument; and enables the points or surfaces of contact to be very broad. Thus all the muscles of the trunk are allowed the same freedom of action with 55 as without the instrument, lateral motion of

the spine at its extremities being provided for by an axial motion or vibration of the uprights or supporting columns upon the screws or pins which attach them to the band below and the cross piece at the top. 60

My invention is represented in the accompanying drawings as follows:

Figure 1 is a rear elevation or back view of the instrument placed in position upon the body. Fig. 2 is a perspective view taken partly from the front. Fig. 3 is a vertical section showing the construction of the stop hinges, and the arrangement of the adjusting screws by which the limit of forward flection is regulated. 70

A is the band around the hips, to which the lower end of the dorsal columns or supports B, B, are connected by the screws *a* in such a manner as to allow of their lateral vibration, the screw serving the purpose of 75 an axis. These supports B, B, are so arranged as to bear upon the angles of the ribs for the purposes already stated, and to do this they are placed upon each side of the spine as shown in Fig. 1. They are connected at the top by the cross piece C as shown. The shoulder straps D, D, are attached to this crosspiece as shown, for the purpose of attaching the instrument to the shoulders of the wearer, and these straps D are connected 80 in front of the wearer by means of the strap H, as seen in Fig. 2. For the purpose of preventing lateral bending of the spine through the point of disease, I attach a band to the dorsal supports, said band being secured at 85 each end to the said supports B, and passing around the body as shown.

The supports B, B, are made in sections, and their longitudinal adjustment is provided for by means of the slots or grooves *g*, and the clamping screws *h*. They are also provided with hinges I, I, I, so constructed and attached as to allow them to render in obedience to a backward pressure against the extremities of the supports B, but at the same 95 time to restrict their flection in the opposite direction so as to prevent a stooping curvature of the spine, while at the same time a backward movement of the extreme portions of the trunk with reference to the middle 100 portion, is freely allowed, and the action of the muscles in that direction is thereby encouraged. The construction of these hinges I, I, I, is more fully shown in Fig. 3. The flection of the lower pair of hinges in that 105 110

direction which would otherwise allow a stooping position of the spine is prevented by the ends of the parts of the supports B, B, meeting each other, and forming with the 5 butt which unites them a stop hinge as shown, and this joint is further supported against flection by the upper portion of the horizontal spring or band plate of the band A, which rises above the joints formed by 10 these hinges. At each of the joints above, it will be observed that the end of one of the parts of the dorsal brace B underlaps the hinge, and the end of the other part to which it is united. This construction and arrangement in connection with the set screw n, 15 forms an adjustable stop by which the instrument may be regulated to fit any form or degree of curvature, and gives a means of changing its adjustment as convalescence progresses, till the spine is brought com- 20

pletely up to its normal position; which is a very important advantage.

I claim as the particular improvements constituting the said invention, and originally and first invented by me:

25

1. A spinal supporter or assistant in which the longitudinal dorsal plates or supports are jointed together in sections in the manner described for the purpose set forth.

30

2. Arranging the dorsal plates in the manner described, by which the pressure which is exerted in a forward direction is thrown upon the angles of the ribs as set forth, instead of upon the vertebræ and vertebral column, as formerly.

CHARLES F. TAYLOR.
